(57) **CLAIM**

The ornamental design for a paint brush and roller handle, as substantially shown and described.

DESCRIPTION

FIG. 1 is a right side rear perspective view of the paint brush and roller handle of the present invention;

FIG. 2 is a right side top perspective view of the paint brush and roller handle of the present invention;

FIG. 3 is a right side elevation view of the paint brush and roller handle of the present invention, the left side view being a mirror image thereof;

FIG. 4 is a right side elevation view of the paint brush and roller handle of the present invention with the thumb screw removed;

FIG. 5 is a front elevation view of the paint brush and roller handle of the present invention;

FIG. 6 is a rear elevation view of the paint brush and roller handle of the present invention;

FIG. 7 is a top plan view of the paint brush and roller handle of the present invention;

FIG. 8 is a bottom plan view of the paint brush and roller handle of the present invention;

FIG. 9 is a right side perspective view of the paint brush and roller handle of the present invention secured to an extension pole;

FIG. 10 is a right side elevation view of the paint brush and roller handle of the present invention with a paint roller; and,

FIG. 11 is a right side perspective view of the paint brush and roller handle of the present invention with a paint brush. Both the broken lines shown in FIGS. 6 and 8 that illustrate the bounds of the claim and the broken lines shown in FIGS. 9 and 10 that represent environmental structure form no part of the claimed design.

1 Claim, 6 Drawing Sheets
